(57) **CLAIM**

The ornamental design of the removable pin, as shown and described.

DESCRIPTION

FIG. 1 is a lower perspective view of the removable pin in accordance with the present invention;

FIG. 2 is an upper perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a rear view thereof; and,

FIG. 9 is a front perspective view of the removable pin in accordance with the present invention, said removable pin inserted into a firearm lower receiver assembly.

The features shown in broken lines in FIG. 9 are for illustrating environmental structure and form no part of the claimed design. More generally, the invention pertains to an ornamental design for an article of manufacture. The article is not limited to the scale shown herein. As indicated in the title, the article of manufacture to which the ornamental design has been applied is a mechanical pin.
